UNITED STATES PATENT OFFICE.

LOUIS P. LAWRENCE, OF PASSAIC, NEW JERSEY, ASSIGNOR TO THE LAWRENCE RAILWAY BRAKE COMPANY, OF NEW YORK.

VALVE FOR AIR OR STEAM PIPES.

SPECIFICATION forming part of Letters Patent No. 392,813, dated November 13, 1888.

Application filed December 16, 1887. Serial No. 258,085. (No model.)

To all whom it may concern:

Be it known that I, LOUIS P. LAWRENCE, of Passaic, in the county of Passaic, State of New Jersey, have invented certain new and useful Improvements in Valves for Air or Steam Pipes, of which the following is a specification.

The object of my invention is to provide a new and improved valve for air or steam pipes of such construction that the water accumulating in the lower parts of the pipes or valve can easily be drawn off through said valve.

The invention consists of a casing and a slotted plug in the same, said casing being also provided with a lateral aperture, which can be brought in communication with the slot of the plug at the same time that the ends of the slot are in communication with the ends of the casing, so as to permit the water that has accumulated in the pipes to blow off through the slot in the plug and through the aperture.

The invention also consists in the combination and construction of parts and details, as will be fully described and set forth herein-after, and finally pointed out in the claim.

In the accompanying drawings, Figure 1 is a side elevation of my improved valve for steam or air pipes. Fig. 2 is a horizontal sectional view of the same on the line xx , Fig. 1. Fig. 3 is a cross-sectional view of the casing, parts being in section and the plug being in elevation.

Similar letters of reference indicate corresponding parts.

The valve-casing A is provided with the tapering cylindrical bore B, for receiving the correspondingly-shaped plug C, having a vertical slot, D. The casing A is provided at each end with an internally screw-threaded neck, E, for attaching pipes, said necks being in communication with the bore B by the slots F. On a level with the bottom of the slot D in the plug C the casing A is provided with a lateral aperture, G, establishing communication between the outer air and the bore. The casing is also provided with an

upwardly-projecting neck, H, having a quadrant-slot, I, in which a pin, J, turns, which is passed through the slot and driven or screwed into an aperture in the plug. A mark, K, is provided in the side of the casing at the top edge. The pin J prevents rotating the plug more than a quarter-turn, and also prevents removing the plug from the casing. In case the plug is to be removed for the purpose of repair or trimming, the pin J must be withdrawn.

As shown in Fig. 3, the plug completely fills the bore, in which it fits very snugly, thus forming an absolutely tight joint, and preventing any escape of steam or air. When the valve is open, the slot D of the plug C is in line with the axis of the necks E, and when the valve is closed said slot is at right angles to the necks. When it is desired to blow off any water that may have accumulated in the pipes, the plug is turned until the pin J is directly above the mark K in the side of the casing. The plug C is then in such a position that one end of its slot D is in communication with the lateral aperture G, and one of the slots F establishes communication between the neck and the bore, and the opposite end of the slot D is in communication with the opposite slot F, establishing communication between the bore and the other neck of the casing. Any water accumulating in the valve or casing will now be forced by steam or air pressure through the slots F into the slot D, and from the same out through the aperture G.

Having thus described my invention, I claim as new and desire to secure by Letters Patent—

The combination of a casing having a cylindrical bore for receiving a plug, slots at diametrically-opposite points of said bore and establishing communication between the ends of the casing and the bore, said casing being also provided with an aperture in its side for establishing communication between the bore and the outer air, a plug mounted to turn in said bore and provided with a transverse slot, the width of which is greater than the distance from the side opening in the casing to

the nearest edge of the adjacent slot, that establishes communication between the bore and the end of the casing, whereby the plug can be so adjusted that its slot is in communication with the two diametrically-opposite slots of the casing and the side aperture of the casing at the same time, substantially as set forth.

In testimony that I claim the foregoing as my invention I have signed my name in presence of two subscribing witnesses.

LOUIS P. LAWRENCE.
